UNITED STATES PATENT OFFICE.

CHARLES L. HEISLER, OF SCHENECTADY, NEW YORK.

LOCOMOTIVE-TENDER.

1,186,776.

Specification of Letters Patent. Patented June 13, 1916.

Application filed September 2, 1915. Serial No. 48,630.

To all whom it may concern:

Be it known that I, CHARLES L. HEISLER, a citizen of the United States, and resident of Schenectady, county of Schenectady, and 5 State of New York, have invented certain new and useful Improvements in Locomotive-Tenders, of which the following is a specification, and which are illustrated in the accompanying drawings, forming a part 10 thereof.

The invention relates to improvements in the coal bin of a locomotive tender, and to improved means for moving the coal forwardly in the bin to bring it within convenient reach of the fireman.

Because of the large size of modern locomotives their firing becomes a serious problem, and the improvements herein shown and described are intended to relieve the 20 fireman, to a considerable extent, of excessive labor in feeding the fuel to the firebox.

To this end the invention consists in part in providing an elevated shoveling platform at the forward end of the fuel bin, and in 25 part of improved means for moving the fuel forwardly in the bin and depositing it upon the shoveling platform.

The invention is fully hereinafter described, and is illustrated in the accompanying 30 drawings, in which—

Figure 1 is a detail vertical longitudinal section through the forward end of a tender and the rear end of a locomotive; Fig. 2 is a similar detail of the forward end of the 35 tender, showing a modified form of construction; and Fig. 3 is a detail plan view of the forward end of the tender, showing the construction illustrated in Fig. 1.

The rear wall of the fire-box of a locomotive is represented at 10, its firing door at 40 11, and its cab floor or firing deck at 12.

In Figs. 1 and 3 a tender of ordinary 45 form is shown, the side walls of its fuel bin being represented at 13, the rear and inclined wall thereof at 14, and its floor at 15.

At 16 there is represented the usual fuel gate.

The floors 12 and 15 of the locomotive cab and tender, respectively, are upon a level, 50 and the intervening space between these floors is bridged, as usual, by means of a plate 17, secured to one of them and slidingly overlapping the other. These floors are considerably below the firing door 11,

as locomotives are usually constructed; and 55 when the fireman is obliged to shovel the coal from the tender floor his labor consists largely in the lifting movement to bring his shovel to the level of the door. Inasmuch as he is required to shovel a large quantity 60 of coal daily this lifting movement is very laborious.

An elevated shoveling platform is shown at 18 and as crossing the forward portion of the coal bin and being on substantially the 65 level of the firing door 11. Preferably, as shown in Fig. 1, this platform is vertically adjustable, thereby adapting it for use in connection with different locomotives having their firing doors at varying elevations. 70 To this end the inclined approach 19 to the elevated shoveling platform consists of a plate hingedly attached, as shown at 20, to the floor of the tender, and, as shown at 21, to the rear edge of the platform 18. 75

Any suitable means may be employed for vertically adjusting and supporting the platform 18. For this purpose there is shown a pair of screw-rods 22, 23, each journaled in a pair of boxes 24, 25, secured 80 to the side wall of the tender, the upper end of the rod being provided with a hand wheel 26 and its lower end being in threaded engagement with a cross-head 27, attached by means of links 28, 29, to the platform 18. 85 When the shoveling platform is lowered from the position shown in Fig. 1, it swings forwardly, owing to the movement of the plate 19 about the pivot 20, and this forward movement is permitted by the link 90 connection between the platform and the cross-head 27.

A coal passer for transferring the fuel to the forward end of the bin is shown as of the general type of the coal passer forming 95 the subject of Letters Patent No. 1,088,418, issued to me February 24th, 1914. In the present structure the transferring means comprises a pair of pushing abutments 30, 31, hinged together, as shown at 32. A push 100 rod 33 connects the rear abutment 30 with a gear rack 34 coöperating with a gear 35, carried by a shaft 36, journaled in suitable boxes mounted on the top wall 37 of the tank of the tender and adjacent the upper 105 edge of the inclined rear wall 19. By means of the gear mechanism the two pushing elements may be drawn up against the wall 14,

and may be advanced to move the fuel forwardly over the floor of the fuel bin and up the incline 19, and deposit it upon the platform 18. A housing 38 covers the gears and 5 also serves as a guide for the rack bar 34, holding it in engagement with the gear 35. A housing 39 extends backwardly from the pusher 20 and slides upon the housing 38, thereby excluding the coal from the operating mechanism.

Any suitable motor 40 may be employed for driving the shaft 36.

In Fig. 2 there is shown a permanently fixed elevated shoveling platform 41. When 15 this form of construction is followed the platform, its inclined approach 42, and its front supporting wall 43 may be made of a single plate. Various other changes may be made in the structure without departing 20 from the scope of the invention.

I claim as my invention—

1. A locomotive tender having a shoveling platform at the forward end of the fuel bin and elevated above the floor of the bin. 25 2. A locomotive tender having a shoveling platform at the forward end of the fuel bin and elevated above the floor of the bin, and an inclined apron leading from the bin floor to the platform.

3. A locomotive tender having a vertically adjustable shoveling floor at the forward end of its fuel bin.

4. A locomotive tender having a vertically adjustable shoveling platform at the forward end of its fuel bin, such platform comprising a pair of plates hinged together and one thereof being hinged to the bin floor.

5. A locomotive tender having a vertically 40 adjustable shoveling platform at the forward end of its fuel bin, such platform comprising a pair of plates hinged together and one thereof being hinged to the bin floor, and a pair of screw rods for adjustably supporting the platform.

6. A locomotive tender having a vertically adjustable shoveling platform at the forward end of its fuel bin, such platform comprising a pair of plates hinged together and one thereof being hinged to the bin floor, a pair of screw rods for adjustably supporting the platform, and link connection between the rods and the platform.

7. A locomotive tender having a shoveling 55 platform at the forward end of the fuel bin and elevated above the floor of the bin, and means for pushing fuel forwardly onto the platform.

8. A locomotive tender having a shoveling platform at the forward end of the fuel bin and elevated above the floor of the bin, an inclined apron leading from the bin floor to the platform, and means for pushing fuel forwardly onto the platform.

65 9. A locomotive tender having a shoveling

platform at the forward end of the fuel bin and elevated above the floor of the bin, means for pushing fuel forwardly onto the platform, such pushing means comprising a reciprocable head, a gear rack attached to 70 the head, a gear engaging the rack, and means for driving the gear.

10. A locomotive tender having a shoveling platform at the forward end of the fuel bin and elevated above the floor of the bin, 75 an inclined apron leading from the bin floor to the platform, means for pushing fuel forwardly onto the platform, such pushing means comprising a reciprocable head, a gear rack attached to the head, a gear engaging the rack, and means for driving the gear.

11. In a locomotive tender having a fuel bin, the combination with such bin of a fuel pusher comprising a reciprocable head, a gear rack attached to the head, a gear engaging the rack, and means for driving the gear.

12. In a locomotive tender having a fuel bin, the combination with such bin of a fuel 90 pusher comprising a reciprocable head, a gear rack attached to the head, a gear engaging the rack, and a fluid motor for driving the gear.

13. A locomotive tender having a fuel bin 95 with an inclined rear wall, a shoveling platform at the forward end of the fuel bin and elevated above the floor thereof, an inclined apron leading from the bin floor to the platform, a fuel pusher reciprocable over the rear wall and floor of the tender and the apron.

14. A locomotive tender having a fuel bin with an inclined rear wall, a shoveling platform at the forward end of the fuel bin and elevated above the floor thereof, an inclined apron leading from the bin floor to the platform, a jointed fuel pusher reciprocable over the rear wall and floor of the tender and the apron.

15. A locomotive tender having a fuel bin with an inclined rear wall, a shoveling platform at the forward end of the fuel bin and elevated above the floor thereof, an inclined apron leading from the bin floor to the platform, a jointed fuel pusher reciprocable over the rear wall and floor of the tender and the apron, and rack and gear mechanism for reciprocating the pusher.

16. A locomotive tender having a vertically adjustable shoveling platform at the forward end of its fuel bin, such platform comprising a pair of plates hinged together, the rearward plate forming an inclined approach to the forward plate when the latter is raised from the floor of the bin.

17. A locomotive tender having a substantially horizontal shoveling platform at the forward end of its fuel bin, such platform being elevated above the floor of the bin.

18. In combination, a locomotive having a firing deck, a tender having a fuel bin and at the forward end thereof a substantially horizontal shoveling platform, such platform being elevated above the firing deck, 10 and power means for pushing fuel forwardly in the bin onto the shoveling platform.

5 19. In combination, a locomotive having a firing deck, a tender having a fuel bin and

CHARLES L. HEISLER.
